RAIL AND FROG CARRYING DEVICE

Frederick F. Zavatkay, New Haven, Conn.

Application September 12, 1942; Serial No. 458,080

8 Claims. (CL. 104—2)

This invention relates to a device for carrying railroad rails, frogs and the like by repairing and construction crews on railroads; and has for an object to provide mechanical means for lifting and carrying the rails on push-cars to eliminate or reduce to a minimum lifting and carrying of the rails and frogs by the workmen.

Another object is to provide an improved and simplified construction for carrying rails, frogs and the like, which may be applied to a standard push-car.

With the foregoing and other objects in view I have devised the construction illustrated in the accompanying drawings forming a part of this specification. It is, however, to be understood the invention is not limited to the specific details of construction and arrangement shown but may involve various changes and modifications within the scope of the invention.

In these drawings:

Fig. 1 is a side elevation of a push-car equipped with my improved lifting and carrying device;

Fig. 2 is an end view thereof;

Fig. 3 is a perspective view of one corner portion of the car and one of the lifting devices, and

Fig. 4 is a perspective view of a carrying stirrup for the rails.

It has been common practice in carrying railroad rails, frogs and the like by construction and repair crews to lift the rails and so forth onto the deck of a push-car, run the car to the desired location and then dump the rails from the car by hand at the sides of the track. Obviously this involves lifting and carrying of the heavy rails by the men, requiring a sizable crew for lifting the heavy rails, frogs, and so forth, besides requiring considerable time and involving considerable danger of injury to the men. The present device was designed to handle and carry the rails mechanically without requiring the lifting of the rails to the deck of the car and to do the lifting and carrying much more expeditiously with much less effort and danger of injury to the workmen.

In the accompanying drawings there is shown a standard push-car having the usual deck 11 mounted on a suitable frame 12 carried by wheels 13 running on the rails 14 of the standard railroad track. Mounted at each end of the deck of this car is a transverse angle iron 15 forming a support for one or more jacks 16. The operating parts of the jack are mounted on a bracket 17 slidable on the support 15 so that it may be shifted to any position desired on this support. The bracket shown has a downwardly extending lug 18 resting against the upright side of the

angle support 15, and at one end of the body portion 19 is provided with a downwardly and inwardly extending hook or flange 20 to engage under the top flange 21 of the angle support 15. This bracket 17 therefore can be slid onto the angle support 15 from either end and shifted to any desired position on the support. If desired notches could be cut in the flange 21 wide enough to permit passage of the hook 20 so that the bracket could be applied intermediate the ends of the support.

Mounted on the body portion 19 of the bracket are the working parts of the jack. Different types of operating mechanism may be employed, but I prefer that shown in the drawings as it is a type of jack mechanism which may be purchased on the market and applied to the bracket 17; the jack shown being known as a scissor-type jack. It comprises a pair of links 22 pivoted to the body 19 at 23 and a similar pair of links 24 pivoted adjacent the other end of the body at 25. The links 24 are pivoted at their upper ends to a block 26, and the links 22 are pivoted at their upper ends to a block 27 threaded on a screw 28 mounted for turning movements in the block 26 and held against longitudinal movement therein. The screw may be operated by any suitable means such as a hand crank 29. Additional links 30 are pivoted to the links 22 adjacent their lower ends and at the upper ends of the links 24. Above the screw are similar links 31 pivoted at their lower ends to the block 26 and at their upper ends to a carrier member 32 of the jack; in this case an inverted channel member, and the links 31 may be pivoted at 33 to the downwardly extending flanges of this member. Similar links 34 are pivoted to the block 27 and the member 32 adjacent their opposite ends, and connecting links 35 similar to the links 30 are pivoted to the lower ends of the links 34 and the block 27 and to the links 31 adjacent to their upper end. It will be seen from this arrangement that by operating the screw 28 the blocks 26 and 27 are moved toward and from each other, and by swinging the various links connected therewith, will raise and lower the carrier member 32. The links 30 and 35 brace the other links to prevent their collapsing sidewise and insure that the member 32 moves up and down in a substantially straight line.

Suspended from the member 32 is a yoke 36 which may be of round rod or other suitable shape with its upper ends 37 bent laterally and resting on the top of the member 32. On each side of these ends 37 are rods 38 welded to the

member 32 to hold the yoke in position and a strap 39 extends over the rods and the ends of the yoke and is secured to the member 32 to retain the ends of the yoke in position between the rods 38. In the lower looped end 40 of the yoke is threaded an adjusting screw 41 having an eye 42 for supporting the lifting tongs 43. A nut 44 may be welded to the looped end 40 to increase the length of the thread and also provide means to be held by a wrench during adjustment of the eye and screw 41 and 42. A nut 45 is mounted on this screw to receive a wrench to facilitate the adjusting operation. The tong is of very simple construction comprising merely the two jaws 46 to engage under the upper or tread flange 47 of a rail and are suspended at their upper ends from the eye 42. They may be held in position by a clamp ring 48, which, after the jaws are in place on a rail flange, may be slid downwardly into position to prevent these jaws releasing the rail. The rail, however, may be easily released by merely lifting or knocking the ring 48 upwardly.

Suspended from each end of the car is a rail stirrup bracket and support 49. This may be of various constructions but a very simple and effective construction is shown, comprising a flat bar 50 supported in the upright position by depending bracket members 51 which may also be flat bars secured to the car by any suitable means, such as bolts 52, and bent into a hook 53 at their lower ends into which the bar 50 is seated and to which it is secured by any suitable means such as bolts or screws 54. After being lifted, the rails 55 are supported from the bar 50 by means of stirrup supports 56. These are of very simple construction and may be of round rod bent to substantially U-shape and at the upper free ends of the side members bent to form downwardly opening hooks 57 which may be merely hooked over the top of the bar 50.

In normal operation a jack is mounted on the angle support 15 at each end of the car with the jack in the lowered position so that the yoke 36 and the tongs 33 are lowered. The tongs may then be placed over the tread flange of a rail, frog or the like between or outside the rails 14, and by operating the two jacks the rail or other member may be lifted to a position against the under side of the bar 50 or the axle 58 connecting the wheels 13 of the car. Stirrups 56 are then placed about the rail and hooked over the bar 50 at each end of the car. The jacks now may be lowered permitting the weight of the rail to rest on the stirrups 56, the stirrups of course being of such a length as to give clearance for placing the hooks 57 over the bar 50 or removing them therefrom when the rail is in the upper position. It will be seen the rail is now supported independently of the jacks by the bar 50, and any suitable number depending on the capacity may be supported from these rods between the wheels. As shown in the drawings, the bars 50 are extended beyond the track rails 14 so that the rails 55a may be lifted and carried outside the track rails 14, the jack supports 15 being also extended beyond these rails 14 for lifting the rails 55a for suspension by stirrups 56a. The deck of the car extends beyond the rails 14 and the rails 55a are therefore carried under the deck of the car.

When the car has been loaded with these rails, frogs and the like it may be pushed to the desired location and the rails and frogs lifted sufficiently by the jacks to permit removal of the

stirrups 56. Then the rail, frog or the like may be lowered to the track bed or ties.

It will be seen from the above that the rails are lifted and loaded on the car by a mechanical means, doing away with the lifting of and carrying the rails by a gang of men, as heretofore required, and also it is not necessary to lift the rails to the deck of the car, but they are carried a short distance above the track rails. This leaves the deck of the car free for carrying other articles, and also means the elimination of the necessity of lifting the rails to the height of the deck of the car. The jacks may be easily and quickly applied to the car and shifted to the desired location for lifting and lowering the rails, and when not in use may be readily removed from the car. Also operation of each jack can be readily performed by a single operator, reducing the number of men required for handling and transporting the rails and leaving the remaining men free for other work.

Having thus described the nature of my invention, what I claim is:

1. In a device of the character described, a railway push-car comprising a deck and two spaced pairs of supporting wheels therefor located with one pair adjacent each of the opposite ends of the deck, a transversely extending mounting member secured at each end of the deck each forming a support and comprising a beam including a transverse flange spaced above the deck, a jack including a bracket resting on top of said flange comprising an upright portion at one side of said beam and provided with a hook engaging under the free edge of the flange at the opposite side of the beam to detachably secure the jack to the support and permit sliding of the bracket along the beam to different positions, means depending from the jack to grip a rail to lift it, and means for operating the jack to lift a rail.

2. In a device of the character described, a push-car comprising spaced sets of wheels and a deck carried thereby, a transversely extending mounting member at each end of the deck comprising an angle iron, a jack including a bracket resting on the angle iron and including a hooked portion to engage under the horizontal flange of the iron to retain the jack thereon and a depending member to engage the upright flange of said iron on the opposite side from the hook to retain the hook over the flange, the jack being slideable along said iron to different positions thereon, means depending from the jack adapted to be secured to a rail for lifting it, and means for operating the jack to lift the rail.

3. In a device of the character described, a push-car comprising spaced sets of wheels and a deck carried thereby, means for mounting a lifting jack at each end of the deck comprising a transversely extending supporting member secured to the car, means securing the jack to said member and permitting sliding of the jack on the member to different positions thereon, means depending from each jack adapted to be secured to a rail for lifting it, means for operating the jacks to lift a rail, a transverse supporting bar mounted at each end of the car below the first mentioned supporting members and suspended therefrom, said bar being located over a rail lifted by the jacks in position to limit upward movement of the rail, and stirrups for supporting a lifted rail having hooks adapted to be engaged over the bars while the rail is held by the jacks

and suspend the rail from the bars when released by the jacks.

4. In a device of the character described, a push-car, means for mounting a lifting jack at each end of the car to be slidable laterally of the car, means depending from each jack adapted to be secured to a rail for lifting it, means for operating the jacks to lift a rail, a transverse support mounted at each end of the car comprising a bar, means for supporting the bars from the car, and substantially U-shaped stirrups adapted to extend under a lifted rail and having hooks at the free ends of its side members, said side members being of a length to permit the hooks to extend over the bar while the rail is held lifted by the jacks and then to hook over the bar to support the rail after it is lowered a short distance by the jacks.

5. In a device of the character described, a push-car, means for mounting a lifting jack at each end of the car comprising a transverse supporting beam secured to the car, a jack mounted on each supporting beam for transverse sliding movement thereon to various positions, means depending from each jack adapted to be secured to a rail for lifting it, means for operating the jacks to lift a rail, transverse supports carried by the car at each end thereof each comprising a bar mounted below the supporting beams and suspended therefrom, and stirrups adapted to engage a lifted rail and each including hooks arranged to be placed over a bar while the rail is held lifted by the jacks and then secure it to the bar for carrying the lifted rails after being lowered a short distance by the jacks.

6. In a device of the character described, a push-car, means for mounting a jack at each end of the car comprising a transversely extending supporting beam including a top flange, a jack

mounted on each support including a bracket slidable along the flange to different positions thereon and including a hook engaging under the free edge of the flange and a depending member engaging the opposite side of the beam to retain the hook on the flange, an upper carrier member, operating means between the carrier member and bracket for raising and lowering said member, a yoke depending from the carrier member, and tongs suspended from the yoke for gripping a rail to lift it by operation of the jack.

7. In a device of the character described, a jack for lifting rails on a push-car comprising a bracket including a body portion adapted to be mounted on an angle shaped support having a top flange and slidable longitudinally on said support to different positions thereon, said bracket including a downwardly extending lug to engage one side of the support opposite the flange and a downwardly and inwardly extending hook spaced from the lug to engage under the flange, lifting mechanism mounted on the bracket, a supporting member depending from the lifting mechanism, and means carried by said supporting member to grip a rail to lift it.

8. In a device of the character described, a railway push-car comprising a deck and supporting wheels therefor, a supporting frame mounted at each end of the deck each comprising an upper transverse beam including a flange adapted for securing a rail lifting jack slidable along the beam to different positions, each frame also including a transverse supporting bar below the beam and members depending from the beam and supporting the bar therefrom, and stirrups for supporting a lifted rail including hooks engaged over the bars to suspend the rail therefrom.

FREDERICK F. ZAVATKAY.
